UNITED STATES PATENT OFFICE.

WALTER O'HARA, OF SEATTLE, WASHINGTON.

PORTABLE HOUSE.

1,152,655.

Specification of Letters Patent.

Patented Sept. 7, 1915.

Application filed November 14, 1912. Serial No. 731,343.

To all whom it may concern:

Be it known that I, WALTER O'HARA, a citizen of the United States, residing at Seattle, in the county of King and State of Washington, have invented certain new and useful Improvements in Portable Houses, of which the following is a specification, reference being had therein to the accompanying drawing.

10 My invention relates to the construction of so-called portable wooden buildings or such as are adapted to be erected by assembling, practically without cutting or fitting, previously constructed units, which if desired may be again separated and re-assembled as before.

An object is to provide a simple construction for double walled houses provided with windows and doors and approximating in 20 appearance houses of non-portable character.

A further object is to provide for building houses of different sizes by using different numbers of similar units, for securing plane 25 interior wall surfaces, strong union of units, air-excluding joints, weights for sash when desired, and ready and secure insertion of window and door frame units.

In the accompanying drawings, Figure 1 30 is a vertical section extending from sills to roof and passing through a window. Fig. 2 a horizontal section passing through a door frame, a window, and one salient angle of the building. Fig. 3 is a horizontal section 35 through a reentrant angle of the building. Fig. 4 is a similar section showing a stud and adjacent portions of an inside partition.

In these figures, A represents a sill resting on a support A', and B one of the joists 40 abutting, midway of the sill, a member B' secured to the sill and projecting from the same to receive in its grooved lower side the usual lip of a water table B² resting on a base board B³. The member B' is rabbeted above 45 to receive upwardly extending wall members B⁴, and a floor B⁵ rests upon the joists and extending to the wall B⁴ overlaps the member B' which is flush with the joists, making here a tight joint so that there is no communication 50 between the space below the floor and the interior of the walls or any space above the plane of the floor. In other words, a section through the building in the plane of the floor would show no cavities 55, but continuous wood.

At each salient angle of the building is

used a post made up of two parts C, C', one having from end to end a wedge-like groove in which fits a corresponding projection or tongue C² of the other, and the two assembled form a post rabbeted to receive the outer boards or sheathing D of the double walls and beveled outwardly from the margins of those boards to receive corner boards, E, closely fitting the post and the boards D 60 upon which they overlap. The two parts of the post form a reentrant angle into which the inner boards, D', of the wall extend, one overlapping the edge of the other as shown, but not attached thereto. Each pair of wall 70 boards is secured to one part only of the post so that the boards and the corresponding part of the post are removable together.

As shown in Fig. 3 the posts at reentrant angles are analogous in construction, the 75 pairs of wall boards being secured to separable tongued and grooved parts of the post; but here no corner boards are used since they would be within the house. In the angle made by the outer wall boards, 80 however, I place a closely fitting member F to aid in excluding air. At intervals, between the corner posts are placed studs or posts each made up of a grooved member G (Fig. 2) and a corresponding member G' 85 having a wedge-like tongue G² to fit in the groove. Both parts are rabbeted to receive wall boards D, D', the inner boards D' being flush with the post while the outer boards D are at some distance within the 90 plane of the outer face of the post which is beveled to form a wedge-like projection over which a correspondingly recessed batten or pilaster G³ is secured by screws G⁴ passing throughout the batten and wall boards into 95 the two parts of the post, respectively, and drawing the batten against the wall boards and binding all the parts together. Obviously, the post may be duplicated as many 100 times as desired, the wall boards and post members to which they are secured forming panels or wall units to be handled without separating their parts. Where a door frame is desired, rabbeted jambs H, secured to properly placed panel studs H', and casings 105 H², H³ are added covering the joints as shown. For windows without weights, posts or studs having tongue and groove parts I, I' are used with external battens I² as side casings. The side jambs I³ are internally flush with the wall boards and posts 110 and are provided with a T-like head I⁴.

which on one side overlaps the batten casing and on the other forms one side of a way for the sash J. An interior casing I⁵ covers the edge of the jamb and the post and 5 overlaps the wall boards, and the jamb is provided with the usual parting strip and interior sash stop. When weights are desired the stud or post member I may be omitted. The window frame has a sill I⁷ 10 and a head jamb I⁶ both grooved and rabbeted to receive the outer and inner wall boards, and the latter are overlapped by the usual casing members.

The structure is provided with a plate 15 member K upon which rest ceiling joists L and rafters M, the remainder of the roof not being here shown. The plate is externally flush with the corner boards E and internally flush with the wall boards, and against 20 its inner face abut ceiling boards N, the angle joint being covered by a molding. The lower side of the plate is grooved to receive a tongue on a member O, itself grooved below to receive a tongue formed on the wall 25 boards flush with its outer face. The inner wall boards overlap this member and abut the plate.

As shown in Fig. 4, inside partitions are 30 analogous in structure, the studs being made of two tongued and grooved parts P, P' each forming one side of a panel or unit section having its face boards Q and Q' seated in rabbet grooves and flush with the corre-

sponding faces of the studs, whereby the partition is plane on both faces and adapted 35 to receive any desired covering or finish.

It is to be noted that the side walls of the building are made up by connecting previously completed, readily shipped unit sections having an internal air space, some of 40 those units containing window frames, and others door frames, and all separably engaging each other to form a transversely rigid whole, and further, that the interior wall spaces are preferably lined with paper or 45 other non-conducting sheets V.

What I claim is:

In a portable wooden building, the combination with a separable corner post having two tongue and groove connected parts 50 alining with the meeting walls, and adapted to receive upon their inner faces overlapping inner wall sheathing, respectively, each post being externally rabbeted to receive the outer sheathing and having, outside the 55 plane of the latter, an inclined face, of rabbeted corner boards each overlapping upon the external sheathing and having an inclined face to wedge against the inclined face first mentioned.

In testimony whereof I affix my signature in presence of two witnesses.

WALTER O'HARA.

Witnesses:

CHARLES M. HOWE,
K. C. HORTON.
